OIL BURNER

Andrew J. Center, Laredo, Tex.

Application December 29, 1932, Serial No. 649,403

4 Claims. (Cl. 299—118)

This invention relates to improvements in burners in which oil and air or steam are atomized and mixed for thorough combustion.

The primary object of my invention is to provide a new and improved oil burner of the above kind embodying an atomizing structure including a rotatable impeller at the burner tip which is actuated by the flowing oil and air or steam acting against the vanes thereof.

10 Another object is to provide a burner of the above character from which the oil and air or steam are discharged in the form of a whirling hollow spray and thoroughly atomized and mixed, and in which the impeller is effectively lubricated by the fuel oil.

A further object is to provide a burner of the above character which is extremely simple and durable in construction and highly efficient in operation.

20 The invention consists in the novel form, combination and arrangement of parts hereinafter more fully described, shown in the accompanying drawing, and claimed.

In the drawing:

25 Figure 1 is a side elevation of an oil burner embodying the present invention, partly broken away.

Figure 2 is an enlarged central longitudinal section thereof.

30 Figure 3 is an end elevation looking toward the right of Figure 2.

Figure 4 is a transverse section on line 4—4 of Figure 2.

Figure 5 is a transverse section on line 5—5 of Figure 2; and

Figure 6 is a side elevation of the impeller.

Referring in detail to the drawing, 5 indicates an outer tube having a tubular burner tip 6 threaded on one end, and a fitting 7 threaded on 40 the other end whose inlet port 8 is adapted for connection with a source of supply of steam or air under pressure. Arranged in spaced concentric relation to and within the outer tube 5 is a fuel conducting tube 9 having threaded engagement at one end in a recess 10 of the fitting 7 in line with another inlet port 11 adapted for connection with a source of oil supply.

The burner tip 6 has an internal beveled valve seat 12 intermediate its ends, and the bore of 50 the burner tip at the discharge end is flared or tapered outwardly as at 13. Arranged in the tip 6 is a valve 14 adapted to seat inwardly against the valve seat 12 and provided with a hollow inwardly extending stem 15 adjustably threaded 55 into the outer end of the oil conducting tube 9

and supported in line with the latter by a perforated disk 16 slidably fitted in the inner end portion of burner tip 6. The valve 14 has outwardly diverging ports 17 therethrough leading outwardly from the outer end of hollow stem 60 15. Projecting outwardly from valve 14 is a stub shaft 18 on which is journaled a conical impeller 19 arranged in the conical outer portion of the bore of burner tip 6 and having longitudinal spirally extending peripheral vanes 20. A spacer 65 sleeve 21 is arranged on the outer end of stub shaft 18 between the hub of impeller 19 and a flat washer 22 secured against the outer end of shaft 18 by a stub screw 23. The inner portion of shaft 18 has an axial passage 24 which communicates 70 at its inner end with the bore of stem 15 and which leads to a radial passage 25 opening through the periphery of shaft 18 intermediate the ends of impeller 19.

It will be seen that by applying a wrench to 75 the head of stud screw 23, the unit composed of valve 14, hollow stem 15 and stub shaft 18 may be turned so as to thread stem 15 into or out of the conducting tube 9 and thereby adjust the valve 14 relative to its seat 12 so that the space 80 15 between the latter will permit the desired flow of air or steam into and from the discharge end of burner tip 6. It will be further seen that a properly controlled flow of oil will be had through conducting tube 9, hollow stem 15, and diverging 85 ports 17, the oil issuing from ports 17 mixing with the hollow spray of air passing the valve 14 and acting with said air, or steam if used instead of air, upon the vanes 20 of impeller 19 so as to rapidly rotate the latter. The use of 90 external power for rotating the impeller is thus rendered unnecessary, and the impeller causes the thorough mixture of oil and air to issue in a whirling hollow spray with the oil thoroughly atomized. The impeller is effectively lubricated by the 95 fuel oil passing through passages 24 and 25 and then between the coacting surfaces of stub shaft 18 and the hub of impeller 19.

From the foregoing description, it will be seen that I have provided a very simple and durable 100 form of atomizing burner which will give exceptionally good results even when using very heavy grades of fuel oil, the whirling air or steam and oil being atomized and thoroughly mixed so as to produce a highly combustible mixture capable of producing an exceptionally hot flame. Minor changes are contemplated within the spirit and scope of the invention as claimed.

What I claim as new is:

1. An oil burner comprising an outer air or 110

- steam conducting tube having a burner tip at the discharge end thereof provided with an internal valve seat, the bore of said burner tip being flared outwardly from said valve seat, an oil conducting tube arranged in spaced concentric relation to and within said outer tube, a valve cooperating with said valve seat and having an inwardly projecting hollow stem communicating with and in adjustable threaded engagement with the discharge end of the oil conducting tube, said valve having diverging ports therethrough communicating with the interior of the hollow stem, a stub shaft projecting outwardly from said valve, means to facilitate turning of the stub shaft and the stem for adjusting said valve toward or from said valve seat, and a tapered impeller journaled on said stub shaft within the flared outer bore portion of the burner tip.
2. An oil burner comprising an outer air or steam conducting tube having a burner tip at the discharge end thereof provided with an internal valve seat, the bore of said burner tip being flared outwardly from said valve seat, an oil conducting tube arranged in spaced concentric relation to and within said outer tube, a valve cooperating with said valve seat and having an inwardly projecting hollow stem communicating with and in adjustable threaded engagement with the discharge end of the oil conducting tube, said valve having diverging ports therethrough communicating with the interior of the hollow stem, a stub shaft projecting outwardly from said valve, means to facilitate turning of the stub shaft and the stem for adjusting said valve toward or from said valve seat, and a tapered impeller journaled on said stub shaft within the flared outer bore portion of the burner tip.
3. An oil burner comprising an outer air or steam conducting tube having a burner tip at the discharge end thereof provided with an internal valve seat, the bore of said burner tip being flared outwardly from said valve seat, an oil conducting tube arranged in spaced concentric relation to and within said outer tube, a valve cooperating with said valve seat and having an inwardly projecting hollow stem communicating with and in adjustable threaded engagement with the discharge end of the oil conducting tube, said valve having diverging ports therethrough communicating with the interior of the hollow stem, a stub shaft projecting outwardly from said valve, means to facilitate turning of the stub shaft and the stem for adjusting said valve toward or from said valve seat, and a tapered impeller journaled on said stub shaft within the flared outer bore portion of the burner tip, said stub shaft having communicating axial and radial bores leading from the bore of the hollow stem to a point intermediate the ends of the stub shaft and the impeller for conducting fuel oil between the coaxing surfaces of said stub shaft and said impeller for lubricating the same.
4. An oil burner comprising an outer air conducting tube having a burner tip at its discharge end provided with an internal beveled valve seat, an oil conducting tube arranged in spaced concentric relation to and within the outer air conducting tube, a valve cooperating with said seat and having a hollow inwardly projecting stem adjustably threaded into the discharge end of the oil conducting tube, said valve having diverging ports therethrough leading from the bore of said hollow stem, a stub shaft projecting outwardly from the valve within the outer end portion of the burner tip, a bladed impeller journaled on said stub shaft, means exteriorly of the burner tip and carried by the stub shaft to facilitate threading of the hollow stem into or out of the oil conducting tube so as to adjust the valve relative to said seat, said burner tip having a cylindrical inner bore portion, and a perforated disk carried by the outer end portion of the hollow stem and slidably engaged in said cylindrical bore portion of the burner tip for sustaining the hollow stem, the valve, and the stub shaft coaxial with the oil conducting tube.
